CLAIM

The ornamental design for a set of billiard balls and pocket markers, as shown and described.

DESCRIPTION

FIG. 1 is a top view of one embodiment of a set of billiard balls and pocket markers, showing the new design;

FIG. 2 is a front view of FIG. 1;

FIG. 3 is a bottom view of FIG. 1;

FIG. 4 is a rear view of FIG. 1;

FIG. 5 is a left side view of FIG. 1;

FIG. 6 is a right side view of FIG. 1;

FIG. 7 is a perspective view of FIG. 1;

FIG. 8 is a top view of second embodiment of my new design for a set of billiard balls and pocket markers;

FIG. 9 is a top view of a third embodiment of my new design for a set of billiard balls and pocket markers;

FIG. 10 is a top view showing the embodiment of FIGS. 1-7 with the markers in an alternate position;

FIG. 11 is a front view of FIG. 10;

FIG. 12 is a bottom view of FIG. 10;

FIG. 13 is a rear view of FIG. 10;

FIG. 14 is a left side view of FIG. 10;

FIG. 15 is a right side view of FIG. 10;

FIG. 16 is a perspective view of FIG. 10;

FIG. 17 is a top view showing the embodiment of FIG. 8 with the markers in an alternate position;

FIG. 18 is a top view showing the embodiment of FIG. 9 with the markers in an alternate position; and,

FIG. 19 is a perspective view showing the embodiment of FIGS. 1-7 and 10-16 in use.

The broken lines are included for the purpose of illustrating set components and/or environmental structure that form no part of the claim to the particular embodiment in which they are shown.
